[57] **CLAIM**

The ornamental design for a tensioning fixture for a musical drum, as shown.

DESCRIPTION

FIG. 1 is a top, front perspective view of a tensioning fixture for a musical drum showing my new design;

FIG. 2 is a left side elevational view thereof;

FIG. 3 is a front elevational view thereof;

FIG. 4 is a right side elevational view thereof;

FIG. 5 is a rear elevational view thereof;

FIG. 6 is a top plan view thereof, the opposite side being a mirror image;

FIG. 7 is a sectional view taken along line 7—7 of FIG. 3;

FIG. 8 is a front elevational view of a modified embodiment of the tensioning fixture shown in FIG. 1; and,

FIG. 9 is a bottom plan view thereof.

The broken lines are shown for illustrative purposes only.
